J. B. MAAG.

Balances.

Patented Feb. 19, 1833.

Feb 19, 1833.

12.

John B. Maag. of the City and State of New York.

Letters Patent.

The schedule referred to in these Letters Patent, and making part of the same, containing a description in the words of the late John Babblet, of New York, of his improvement in the Balance,

Be it known that I, John Babblet, of the City and County of New York, have invented and applied to use a new & useful improvement in the construction of Balances, or weighing scales, made of several levers connected in various proportions so that a small weight shall equipose the sum of the others of all their powers.

A true description of the construction of such Balances with any improvements and inventions theron & the manner of their use is as follows viz.

O. T. S. Fig 1 of the accompanying Draft is a strong wooden frame upon which the machinery is constructed, & is either fixed in solid Masonry or made moveable on wheels as may be most convenient for the different purposes to which it is to be adapted. The weighing platform which forms the whole top of the lower part of the frame & on which the load is placed, rests on the iron levers A, B, C, D, uniting near B, two D. E. F. X uniting also near the point of its contact with said levers being at the points 1, 2, 3, 4, the free shorter arm of these levers being fixed in A, C, D, F. E. & resting on the points connected with the frame as a fulcrum A, B, & C, B is arm uniting near B, form a lever having its fulcrum A & C, the weight on the platform being applied equally to the point 1 & 2 & the greater arm of the lever is inserted in the moveable rectangular iron base piece B. Fig 2. by means of which one half of the whole weight becomes suspended on the third lever, G, H. at the point I. D. E. F. X, two arms uniting near X, also from another lever having its fulcrum in D. F. X, the weight or load being applied to the point 3 & A. & the extremity of its greater arm at X, resting on the moveable rectangular iron base piece X, by means of which the the other half of the whole weight is suspended on the same lever G, H. with at the same point I. The small iron base piece B, G, H, I, 2 being proportionably upon an axis or two small iron pins like a balance.

radially to the lever G. H., an extension of it in E. A. forms the pivoting point of the lever G. H., the lever G. H. has its fulcrum in F., resting upon a firm support fixed in the frame O. T. S. & the extremity of its arm G. is attached to the shorter arm of the lever I. K. by the perpendicular connecting rod I. G. which now suspends the lever I. K. with the load when the balances are in action or in a state of suspension.

I. K. is another lever which may be called the balance beam having its fulcrum in I. A. from the greater arm of which at K., the scale W containing the weights is suspended.

The fulcrum I. A. is a moveable perpendicular iron bar, serrated on the inner edge for the purpose of admitting the passage of a small wheel turned by a windlass T. of which it forms part being supported by a pivot in the perpendicular post, T. V. by means of which moveable bar, wheel & windlass, the whole combination of levers will be weighty platform is either elevated or depressed according to circumstances, elevated for the purpose of being put in a state of suspension when the true weight is to be ascertained or depressed that the machine may be at rest.

The greater arm of the lever I. K., being kept confined by a movable iron the projecting iron bar T. P. is by means of the small rectangular piece of iron P. R. with a wooden handle which moves on a pivot at Q. raised up and lowered under it.

The windlass being then turned up the levers are all raised with it & brought to act upon and bear up the load on the platform in a state of suspension, & being able to keep the platform free from contact with the frame & prevent all friction with it while the true weight is being ascertained.

When the windlass is let down the whole platform rests upon the four supports 6. 7. 8 & 9. fixed in the frame and thus the whole construction of the machine when not in operation is preserved from injury and is in a steady fixed position for the reception of a load. of the lever having S. V. T. which serves to ascertain the equilibration of the weights in the scale W with the load S. a moveable attached to the end of the scale beam I. K. & T. is stationary and fixed to the upright perpendicular post so that when the post meets the scale beam is exactly horizontal & the true weight indicated.

Fig. 2 is a draft showing the particular & exact insertion of the two lever being into the moveable rectangular iron head piece B. V. K. and then connecting with the lever G. H. & dependence upon the arms E. A.

Fig. 3. is a lateral view of Fig. 2. a front view of the rectangular iron head piece. Fig. 5. is a view of an weighing platform attached from the frame.

15

and sloping also the point by which it rests upon the lower lines.
The 2d. is a view of the machine at rest, that which is specially claimed as a
convention & improvement are the disposition & distribution of the whole weight equal
to upon the four lower lines to each unite their power with the total weight in the
point P^o of the line G, H, together with the construction position & combination
of these lower lines.

Under the construction, position & operation of the moveable serrated iron bar forming
a fulcrum for the scale beam, together with the wind-up & wheels connected
therewith by which the whole scale and platform are acted upon & suspended in
equilibrium.
